8 Claims.

(Cl. 57—6)

1

This invention relates to devices for applying thermoplastic tape and the like to electric cables and securing its adhesion thereto.

It is often necessary to wrap an electric cable with insulating tape, as for example when making joints or repairing damaged cable; and it may be desired to have this insulating tape of thermoplastic material or of the kind impregnated or coated with thermoplastic material and to cause this thermoplastic material to "weld" under the application of heat to a sheath of thermoplastic material on the cable. Again, in the case of rubber-coated tape it may be desirable to vulcanize the rubber during wrapping. In both these cases it is a question of applying heat to the tape during the wrapping process, and the present invention is concerned with the provision of a device or tool for effecting the simultaneous wrapping and heating.

The invention consists in such a tool comprising means for applying the tape to the cable and means for passing a high-frequency electric current through the tape at substantially the same time as the tape is being applied to the cable.

The description which follows relates to the accompanying drawings in which Figs. 1, 2 and 3 represent, in diagrammatic perspective, three embodiments of the invention.

In Fig. 1 is shown a cable having an inner metallic conductor W and an outer layer P of insulating material. Around this cable a tape T of insulating material is to be wound in a continuous helix, the winding process involving the application of heat, as when the tape T and outer layer P comprise thermoplastic material. The tool by which this simultaneous winding and heating is effected consists of a box B having a suitable handle H and having an extension arm on one side for carrying the spool or roll R of insulating tape.

The heating is effected by subjecting the tape, being a dielectric material, to a high-frequency electric current so that, as is well known, heating results from the high-frequency current passing through the dielectric. Accordingly a generator unit is housed within the box B, and one of its output leads is taken directly to an electrode E, which forms the bottom of the box B and is shaped to the contour of the cable. The other lead L is taken from the box B to the inner conductor W of the cable.

In use the tape T from the roll R is passed through a slot F in the curved electrode E on to the cable itself, so that as the tool is rotated by hand around the cable as shown by the arrow, the tape is unwound from the supply roll R and

2

wound onto the cable. At the same time a high frequency potential is applied across the tape and the insulation P on the cable between the outer electrode E and the inner conductor W. In this way the tape lying under the electrode E is heated, with consequent "welding" to the cable insulation and to the adjacent layers of tape.

The progressive axial movement of the tool ensures that the tape is laid in helical form with any desired amount of overlap.

The element constituting the inner electrode of the high frequency system has been shown as the innermost wire W; but obviously this is not necessarily so, and the choice will depend upon the structure of the cable being treated. For example, as shown in Fig. 3, if there is a metallic barding BR underneath the outermost layer of thermoplastic material, the lead L may be connected to this barding instead of to the core. Again it may not be possible to obtain access to any metallic interior part of the cable, so that the heating current must be passed right through the cable from one side to the other. Fig. 2 shows a modified tool suited to this purpose.

In Fig. 2 the lead L of stout material is taken around in the circumferential direction to a counter-electrode C of any desired form. The electrode C is shown, for example, as comprising a wheel situated more or less diametrically opposite to the centre of the other electrode E.

What is claimed is:

1. A tool for winding tape onto a cable or the like comprising a high-frequency generator, a tape-spool carrier mounted on a member adapted to engage the periphery of the cable under which member the tape from the spool is fed onto the cable, an electrical connection from one output terminal of the generator to said member, and a lead from the other output terminal of the generator for making electrical connection to a metallic interior component of the cable.

2. A tool for winding tape onto a cable or the like comprising a high-frequency generator, a tape-spool carrier mounted on one of a plurality of members adapted to engage the cable on substantially opposite sides and to press the tape onto the cable, and connection from the output terminals of said generator to said members.

3. A tool for winding tape onto a cable or the like comprising means for wrapping tape around said cable, said means having a source of high frequency current and a pair of electrodes for application of the high frequency current to the cable, and at least one of said electrodes being

caused to move about the periphery of the cable as the tape is being wrapped therearound.

4. A tool for winding tape onto a cable according to claim 3 wherein said one of said electrodes includes a portion shaped to conform substantially to the contour of the cable.

5. A tool for winding tape onto a cable according to claim 3 wherein said one of said electrodes includes a wheel adapted to contact the periphery of the cable.

6. A tool for winding tape onto a cable according to claim 3 wherein the other of said electrodes includes means for connecting it to a conductor portion of said cable.

7. A tool for winding tape onto a cable according to claim 3 wherein the other of said electrodes includes means for locating it at a point circumferentially spaced around the cable from said one electrode.

8. A tool according to claim 3 wherein said one 20

electrode includes a portion shaped to conform substantially to the contour of the cable and the other of said electrodes includes a wheel adapted to contact the cable at a point circumferentially spaced about said cable from said one electrode.
